United States Patent Office

Des. 195,765
Patented July 30, 1963

195,765

DRIVE-IN RETAIL BUILDING

Dwight A. Harrison, 1201 Central Ave. E.,
Hampton, Iowa

Filed Dec. 13, 1962, Ser. No. 72,832

Term of patent 14 years

(Cl. D13—1)

Fig. 1

Fig. 2

Fig. 3

Fig. 4

FIG. 1 is a front elevational view of the drive-in retail building, showing my new design;

FIG. 2 is a rear elevational view thereof;

FIG. 3 is a side elevational view thereof looking from the right in FIG. 1; and

FIG. 4 is a side elevational view thereof looking from the left in FIG. 1.

The dominant features of my design reside in the portions shown in full lines.

I claim:

The ornamental design for a drive-in retail building, substantially as shown and described.
